Primary Examiner — L. A. Grabenstetter

(57) **CLAIM**

The ornamental design for a phone wallet case, as shown and described.

DESCRIPTION

FIG. 1 is a front, top, right side perspective view of a phone wallet case showing my-new design, in a closed state; FIG. 2 is a back, bottom, left side perspective view thereof; FIG. 3 is a front view thereof; FIG. 4 is a back view thereof; FIG. 5 is a left side view thereof; FIG. 6 is a right side view thereof; FIG. 7 is a top view thereof; FIG. 8 is a bottom view thereof; FIG. 9 is a front, top, right side perspective view of one partially open state of the phone wallet case thereof; FIG. 10 is a front, left side perspective view of one partially open state of the phone wallet case thereof; FIG. 11 is a back, bottom, left side perspective view of one partially open state of the phone wallet case thereof; and, FIG. 12 is another front, top, right side perspective view of the phone wallet case in a closed state, shown in a usage state and combined with an environmental strap.

The broken lines, and unshaded surfaces bound by broken lines, depicting features of the phone wallet case form no part of the claimed design. The broken lines depicting stitching forms no part of the claimed design. The broken line strap depicted in FIG. 12 represents environmental subject matter included for the purpose of demonstrating a state of use and forms no part of the claimed design.

1 Claim, 12 Drawing Sheets
